UNITED STATES PATENT OFFICE.

WALDO W. VALENTINE, OF BUFFALO, NEW YORK.

IMPROVEMENT IN VEHICLE-WHEELS.

Specification forming part of Letters Patent No. 222,611, dated December 16, 1879; application filed February 20, 1879.

To all whom it may concern:

Be it known that I, WALDO W. VALENTINE, of Buffalo, in the county of Erie and State of New York, have invented certain new and useful Improvements on a Vehicle-Wheel; and I do hereby declare that the following description of my said invention, taken in connection with the accompanying sheets of drawings, forms a full, clear, and exact specification, which will enable others skilled in the art to which it appertains to make and use the same.

This invention has general reference to improvements in vehicle-wheels; and it consists in the peculiar combination of parts and details of construction, as hereinafter first fully set forth and described, and then pointed out in the claims.

In the drawings already mentioned, which serve to illustrate my said invention more fully, Figure 1 is a front elevation of my improved vehicle-wheel, showing its general arrangement and the location of parts. Fig. 2 is a plan of the hub. Fig. 3 is an end view of the same, illustrating the disposition of the spokes. Fig. 4 is a perspective view of the wedge-key used for locking the spoke-bands. Fig. 5 is a plan of a hub slightly modified. Fig. 6 is a longitudinal sectional elevation in line $\alpha\alpha$ of Fig. 8. Fig. 7 is a similar view, illustrating the manner of inserting the spokes. Fig. 8 is an end view of the hub. Fig. 9 is a transverse section through the tire and felly. Fig. 10 is a similar view, showing the spokes in position. Fig. 11 is a sectional view of a fragment of the hub.

Like parts are designated by corresponding letters of reference in all the various figures.

A is the felly, and B the tire, of my wheel, made in the usual manner. C is a band placed into the inner circumference of the felly A. d , d' are the spokes, made of wire of light gage, bent into a form somewhat resembling an inverted letter U, and represented in Fig. 10.

E is the wooden hub. It is surrounded by two metallic bands, F F', having their joint midway between the spokes d d' . These bands have wrench-sections f, by means of which they are manipulated in a manner hereinafter described. They are, furthermore, provided with a series of apertures, g, for the reception of the ends of the spokes d d' .

In the edges of the bands F F' are a series of notches, g' , to admit a wedge-key, g'' , Figs. 4 and 6, wherewith the bands F F' are held in proper position after the spokes are inserted and tensioned. The number of notches g' in one band does not correspond with that in the other band, so that they will not register when the bands are placed together. The object of thus making these notches differential is to provide for means of tensioning the spokes and then locking the bands F.

In the wooden hub E there are two grooves, H, placed a distance apart equaling the distance between the members d d' of the spokes, plus double the length of the bent part of the spokes within the hub-bands F F'.

In putting together a wheel of the kind described, the inner band, C, is first placed into the felly A. This felly has in its perimeter a series of notches, j, Fig. 9, equaling in number that of the spokes d or d' , and in its faces grooves j' , to receive the upper part of said spokes. The parts d'' of these spokes are as wide as the felly or tire, and these parts are placed into the notches j , and the members d d' , with their ends, into the apertures g in the bands F F', said bands being placed upon the hub E so that said apertures register with the grooves H. All the spokes being thus inserted, the tire B, or a suitable temporary tire, is placed over the felly, and the hub-bands F F' forced together until their faces meet. The hub-bands being thus forced together cause the ends of the spokes to bend at, or nearly at, right angles, and thereby to be clinched on the inner side of said bands, at the same time embedding themselves into the protuberant part of said wooden hub E. Now the two bands F F' are taken hold of by the wrench-sections f with any suitable wrench, and turned in opposite directions as far as necessary, to tension all the spokes simultaneously, after which the key g'' is placed into that pair of notches g' which will register, to keep the hub-bands in their proper position.

I have heretofore said that the notches g' are differentially arranged, so that when one set of notches register the next set will slightly deviate, the difference increasing with every succeeding set of notches. By this arrangement there will always be one set of notches

that register and allow the hub-bands being locked.

This construction enables me to retension the spokes, if necessary, by simply withdrawing the key, slightly rotating the bands, and reinserting the key.

For the spokes $d d'$ I prefer to use wire of, say, No. 14 gage for a wheel of from three to four feet in diameter, adapted for light vehicles, and comparatively larger wire for stronger wheels; but since the latter wire is not so readily bent, because the wooden hub E is not capable of offering sufficient resistance, I modify the construction of the hub and bands by first placing a tube, G, Fig. 7, upon the wooden hub E, which tube has a protuberant part, g'' , Fig. 6, and two side projections, i . This tube being secured to the hub, the bands F F' are placed upon it, and the spokes $d d'$ inserted before they are pushed together, the manner of clinching said spokes being identical with that already described, except that the parts $i i$, being made of metal, are better able to bend the ends of the said spokes. This method of construction is clearly illustrated in Figs. 5, 6, and 7.

The bands F F' (shown in Fig. 2) necessitate drilling of the apertures g for receiving the spokes $d d'$. To avoid this extra work, I provide the bands shown in Figs. 5, 6, and 7 with notches g in their edges, which notches may be produced in the process of casting said bands. This construction is cheaper than the one previously described; but it necessitates a change in the location of the locking-notches g' , which, as shown in Figs. 5, 6, and 7, are discarded and holes substituted. These holes are differentially arranged, and therefore afford all the advantages of the differentiating-notches illustrated in Fig. 2.

My wheel has two divisions or sections of spokes—that is to say, all the spokes d on one side of the felly A, being those fastened in the band F, form one division or section, and the spokes d' , fastened in the band F' on the other side of the felly, form the second division or section. Hence, in speaking of a spoke-division, reference is had to all the spokes on one side or the other of said felly, while in referring to a hub-section one side or the other of the hub with its corresponding band is meant.

A peculiar feature of my wheel is that the two divisions of the spokes are parallel, or nearly parallel, to each other, or, in other words, the wheel is not dished. This I have designed to overcome one great objection to metallic-spoked wheels, which is that when the wheel receives any thrust sidewise those spokes on the side opposite from that from which the strain is applied are tensioned often beyond their limit, while those on that side nearest to the source of disturbance are slackened.

Now in my wheel, where both divisions are parallel, all the spokes partake of and divide

themselves into this strain, and therefore offer greater resistance to the disturbing cause than one division alone is capable of resisting.

The spokes in my wheel do not act in the same manner as wooden or rigid spokes in common wheels, because they sustain their load by their tensile strength, the upper half of said spokes only supporting the hub and vehicle. Although this would at first sight seem to detract from the strength of the wheel, it is nevertheless a fact that a wheel constructed as described is far stronger than a more rigid wheel, owing to its superior flexibility and the combined tensile strength of one-half of all the spoke-wires, and it is, therefore, more durable and rides easier than any other wheel with which I am acquainted.

In wheels which are placed upon the market without tires, I shall furnish them either without the spokes being tensioned, or I shall tension them when under the influence of a temporary removable tire, so that the contraction of the tire proper will not cause a corresponding contraction of the felly, and consequently a looseness of the spokes.

Heretofore wheels were made with wire spokes and metallic rims having a T-shaped cross-section, and the spokes passed through an inwardly-projecting flange or the web of said rim, the spokes crossing each other near said web. Such spokes were fastened with their ends to rings placed upon movable pieces upon the axle-box, and were tensioned by moving such pieces apart, and thereby varying the angle between the spokes, or, in other words, increasing the dish of the wheel. In this construction the spokes are not tensioned by rotating that part of the hub to which the spokes are fastened, so that this method of tensioning said spokes is entirely distinct from the construction hereinbefore described, while the objection against dished wheels applies with all its force to such wheels.

I am aware that trussed or suspension wheels are not new, and I therefore do not broadly claim a wheel composed of a rim and metallic spokes fastened with one end in or to said rim and with the other end to the hub or a part of the hub; nor do I broadly claim tensioning such spokes after they are fastened to the said rim and hub; but

What I do claim as new, and desire to secure to me by Letters Patent of the United States, is—

1. A wheel constructed with flexible spokes consisting of members $d d'$, the ends of which are secured to bands F F', said members passing to and across the outer periphery of the felly without crossing each other, as specified.

2. A wheel in which the felly or rim is connected by flexible spokes with the hub, said spokes passing over the said felly on its outer periphery at various points, and connecting the bands F F' with their corresponding side and point of said felly in a direct line, as stated.

3. A trussed wheel in which the spokes are fastened in bands and strained or tensioned by rotating said bands in opposite directions, as specified.

4. A trussed wheel in which tension is given simultaneously to all the spokes in equal degree by rotating those parts of the hubs to which the respective ends of the spokes are fastened.

5. A wheel in which the spokes do not pierce the felly, but are conducted around it upon three of its sides, and let into said sides to the depth of the diameter of said spokes.

6. A wheel having two spoke-divisions tensioned by revolving those parts of the hub to which the respective ends of said spokes are fastened in opposite directions, said hub parts being provided with means, substantially as described, for retaining the spokes in a tensioned state, as specified.

7. A wheel having two spoke-divisions fastened in two hub-bands, said spoke-divisions being tensioned by revolving the hub-bands in

opposite directions, and retained in a tensioned state by locking the hub-bands, as and for the purpose specified.

8. A wheel having two spoke-divisions tensioned by revolving those parts of the hub to which the respective ends of said spokes are fastened in different directions, said hub parts being provided with a differential fastening, as and for the use and purpose indicated.

9. The combination, with the hub E, having the bands F F', provided with a differential fastening, of the spokes d d', secured within said hub-bands, and tensioned by revolving said hub-bands in opposite directions, as stated.

In testimony that I claim the foregoing as my invention I have hereto set my hand and affixed my seal in the presence of two subscribing witnesses.
